ELECTRICAL CONNECTOR

Eugene E. Holke, St. Louis, Mo., assignor to James R. Kearney Corporation, St. Louis, Mo., a corporation of Missouri

Application April 29, 1949, Serial No. 90,320

10 Claims. (Cl. 287—77)

1

This invention relates generally to electrical connectors and more specifically to electrical connectors of the type comprising a pair of jaw members that are drawn toward each other to the clamping positions thereof by bolts or other screwthreaded elements, the predominant object of the invention being to provide an electrical connector of the type mentioned which is of such improved construction and arrangement that it is capable of performing its intended function in an improved and highly efficient manner.

Fig. 1 is a plan view of the improved electrical connector of the present invention.

Fig. 2 is a vertical section taken through the connector shown in Fig. 1 showing a pair of electrical conductors associated therewith.

Fig. 3 is a vertical section taken on line 3—3 of Fig. 2.

Fig. 4 is a fragmentary, horizontal section taken on line 4—4 of Fig. 2.

Fig. 5 is a fragmentary, horizontal section taken on line 5—5 of Fig. 2.

In the drawing, wherein is shown for purposes of illustration, merely, one embodiment of the invention, A designates the improved connector generally. The connector A includes a jaw member 1 which comprises a top wall portion provided with an arcuate wire seat 2 that extends transversely of the under side of said top wall portion, said jaw member 1 including, also, opposed, bifurcated side wall portions 3, the spaced legs 3' of each of which extend downwardly from the top wall portion of the jaw member 1, with the inner edges of said spaced legs 3' merging into the wire seat 2 (Fig. 2). The electrical conductor A includes, also, a jaw member 4 which is aligned with the jaw member 1, said jaw member 4 being provided with outwardly extended lug portions 5 which are projected from the opposite side faces of said jaw member 4. The lug portion 5 at each side of the jaw member 4 is projected into the space between the spaced legs 3' at the corresponding side of the jaw member 1, and the jaw member 4 is provided with a transversely extended, concave wire seat 6 of which arcuate top faces of the lug portions 5 form parts.

The top wall of the jaw member 1 is provided with spaced openings 7 and the jaw member 4 is likewise provided with spaced openings 8, the spaced openings 8 of the jaw member 4 being aligned with the spaced openings 7 of the jaw member 1 and said openings 8 having screwthreaded walls. The jaw members 1 and 4 are connected together by means of a pair of bolts

2

9 and 10, each of said bolts being extended through a pair of aligned openings 7 and 8 and with screwthreaded shank portions of said bolts screwthreadedly engaging the screwthreaded walls of the openings 8 of jaw member 4. It is to be noted that the shank of the bolt 10 is shown as being screwthreaded throughout its entire length, while the shank of the bolt 9 is screwthreaded throughout only a portion of its length, as is shown clearly in Fig. 2. In other words, the bolt 9 is provided with a smooth shank portion 9' which extends from the under side of the head of said bolt to the inner end of the screwthreaded portion of said bolt shank and said smooth shank portion is of substantially less diameter than the outside diameter of the screwthreaded shank portion of the bolt 9.

The improved electrical connector A includes a spacer member 11 which is interposed between the pairs of spaced legs 3' of the jaw member 1 that are located at opposite sides of the connector, and intermediate of the wire seats 2 and 6 of the jaw members 1 and 4. The spacer member 11 is provided with opposed, concave wire seats 11' which extend longitudinally thereof, and fixed to said spacer member is a substantially L-shaped element 12, the horizontal leg of which is provided with an opening 13 formed therethrough through which the shank of the bolt 10 extends. The spacer member 11 has formed therein a vertical groove 14 (Fig. 5) which receives the vertical leg of the element 12, portions 15 of the spacer member at opposite sides of the groove 14 being swaged into engaging contact with the outer face of said vertical leg of said L-shaped element so as to securely attach said L-shaped element to said spacer member.

By referring to Fig. 4 it will be noted that the opening 1 of the jaw member 1 is of irregular, noncircular shape when the connector A has been assembled. Because of this arrangement the bolt 9 may not be withdrawn through said opening 1 so as to completely disengage said bolt 9 from the connector structure, the irregularly shaped opening 1 of the jaw member 1 being of insufficient size in the direction of the length of said jaw member 1 to permit passage therethrough of the screwthreaded shank portion of the bolt 9. When the jaw member is made originally the opening 1 through which the bolt 9 passes is round, as is shown by dotted lines in Fig. 4, and the adjacent end portion of said jaw member 1 is shaped as is also shown by dotted lines in Fig. 4. However, after the connector A

has been assembled with the bolts 9 and 10 in place therein, the end portion of the jaw member 1 located adjacent to the opening 7 through which the bolt 9 extends, is subjected to a blow which deforms said end portion and causes said opening 7 to assume the irregular shape shown in Fig. 4 so as to prevent passage therethrough of the screwthreaded shank portion of the bolt 9.

In the use of the connector A, electrical conductors Ca and Cb are disposed in place between the wire seats 2 and 6 of the jaw members 1 and 4 and the wire seats 11 of the spacer member 11, as is shown in Fig. 2. The bolts are then drawn up to move the jaw members 1 and 4 into clamping relation with respect to the conductors Ca and Cb. Also, because of the deformed opening 7 in the jaw member 1 through which the shank of the bolt 9 extends, said bolt 9 may not be entirely disengaged from the connector structure, and because of the attachment of the spacer member 11 to the bolt 10, through the instrumentality of the L-shaped element 12, said spacer member may not be accidentally detached from the connector structure.

I claim:

1. An electrical connector comprising a first jaw member having openings formed therethrough, a second jaw member having screwthreaded openings formed therethrough, and a pair of bolts the shank portions of which extend through the openings formed through said first jaw member and have screwthreaded portions which are screwthreadedly seated in the openings formed through said second jaw member, said first jaw member being provided with means at the opening thereof through which the shank portion of one of said bolts extends which prevents passage of the screwthreaded shank portion of said bolt through said opening.

2. An electrical connector comprising a first jaw member having openings formed therethrough, a second jaw member having screwthreaded openings formed therethrough, and a pair of bolts the shank portions of which extend through the openings formed through said first jaw member and have screwthreaded portions which are screwthreadedly seated in the openings formed through said second jaw member, said first jaw member being provided with means at the opening thereof through which the shank portion of one of said bolts extends which prevents passage of the screwthreaded shank portion of said bolt through said opening, said means comprising an integral part of said first jaw member.

3. An electrical connector comprising a first jaw member having openings formed therethrough, a second jaw member having screwthreaded openings formed therethrough, and a pair of bolts the shank portions of which extend through the openings formed through said first jaw member and have screwthreaded portions which are screwthreadedly seated in the openings formed through said second jaw member, said first jaw member being provided with means at the opening thereof through which the shank portion of one of said bolts extends which prevents passage of the screwthreaded shank portion of said bolt through said opening, said means comprising an integral deformed part of said first jaw member.

4. An electrical connector comprising a first jaw member having openings formed therethrough, a second jaw member having screwthreaded openings formed therethrough, and a

pair of bolts the shank portions of which extend through the openings formed through said first jaw member and have screwthreaded portions which are screwthreadedly seated in the openings formed through said second jaw member, said first jaw member being provided with means at the opening thereof through which the shank portion of one of said bolts extends which prevents passage of the screwthreaded shank portion of said bolt through said opening, said means comprising an integral deformed part of said first jaw member which constitutes a part of the wall of said opening.

5. An electrical connector comprising a first jaw member having openings formed therethrough, a second jaw member having screwthreaded openings formed therethrough, and a pair of bolts the shank portions of which extend through the openings formed through said first jaw member and have screwthreaded portions which are screwthreadedly seated in the openings formed through said second jaw member, the opening of said first jaw member through which one of said bolts extends being of such shape as to prevent passage of the screwthreaded shank portion of said bolt through said opening.

6. An electrical connector comprising a first jaw member having openings formed therethrough, a second jaw member having screwthreaded openings formed therethrough, and a pair of bolts the shank portions of which extend through the openings formed through said first jaw member and have screwthreaded portions which are screwthreadedly seated in the openings formed through said second jaw member, the opening of said first jaw member through which one of said bolts extends being of such irregular shape as to prevent passage of the screwthreaded shank portion of said bolt through said opening.

7. An electrical connector comprising a first jaw member having openings formed therethrough, a second jaw member having screwthreaded openings formed therethrough, a pair of bolts the shank portions of which extend through the openings formed through said first jaw member and have screwthreaded portions which are screwthreadedly seated in the openings formed through said second jaw member, a spacer member disposed between said first and second jaw members, an attaching element associated with said spacer member and having an opening formed therethrough through which the shank portion of one of said bolts passes, and swaged portions of said spacer member which secure said attaching element to said spacer member.

8. An electrical connector comprising a first jaw member having openings formed therethrough, a second jaw member having screwthreaded openings formed therethrough, a pair of bolts the shank portions of which extend through the openings formed through said first jaw member and have screwthreaded portions which are screwthreadedly seated in the openings formed through said second jaw member, a spacer member disposed between said first and second jaw members, an attaching element associated with said spacer member and having an opening formed therethrough through which the shank portion of one of said bolts passes, said spacer member being provided with a groove that receives a portion of said attachment element, and swaged portions of said spacer mem-

5

ber which secure said attaching element to said spacer member.

9. An electrical connector comprising a first jaw member having openings formed therethrough, a second jaw member having screw-threaded openings formed therethrough, a pair of bolts the shank portions of which extend through the openings formed through said first jaw member and have screwthreaded portions which are screwthreadedly seated in the openings formed through said second jaw member, a spacer member disposed between said first and second jaw members, an attaching element associated with said spacer member and having an opening formed therethrough through which the shank portion of one of said bolts passes, said spacer member being provided with a groove that receives a portion of said attaching element, and swaged portions of said spacer member at the opposite sides of said groove which secure said attaching element to said spacer member. 20

10. An electrical connector comprising a first

6

jaw member having openings formed therethrough, a second jaw member having screw-threaded openings formed therethrough, a pair of bolts the shank portions of which extend through the openings formed through said first jaw member and have screwthreaded portions which are screwthreadedly seated in the openings formed through said second jaw member, a spacer member disposed between said first and second jaw members, an attaching element of L-shaped form associated with said spacer member and having an opening formed therethrough through which the shank portion of one of said bolts passes, said spacer member being provided with a groove that receives a portion of said attaching element, and swaged portions of said spacer member at the opposite sides of said groove which secure said attaching element to said spacer member.
